Specification for Design.

Patented May 3, 1921.

Application filed September 18, 1920. Serial No. 411,321. Term of patent 3½ years.

To all whom it may concern:

Be it known that I, FREDERICK MAX PORITZ, a citizen of Germany, having declared my intentions of becoming a citizen of the United States, residing in the borough of Manhattan, city, county, and State of New York, have invented a new, original, and ornamental Design for Chandeliers, of which the following is a specification, refer-

ence being had to the accompanying drawing, forming part thereof.

Figure 1, is a perspective view of a chandelier, showing my new design; and

Fig. 2 is a view of the under side thereof.

I claim:

The ornamental design for a chandelier, as shown.

FREDERICK MAX PORITZ.
